ABSTRACT OF THE DISCLOSURE

This invention provides a method for heating low temperature fluids by using a recycled equilibrium process fluid as a heat exchange intermediate. By using this process fluid rather than a separate intermediate fluid, advantages are gained, in that, less heat exchange area is required, no separate handling facilities are needed for the intermediate fluid, and intermediate fluid losses are reduced.

BACKGROUND

The present invention relates generally to a method for heating low temperature fluids. More particularly, the process of the instant invention provides a method for heating low temperature fluids by using a recycled equilibrium process stream as a heat exchange media. The teachings of the instant invention are particularly applicable in the regasification of liquefied natural gas, hereinafter referred to as LNG.

Natural gas is often available in areas remote to where it will be ultimately used. Quite often the source of this fuel is separated from the point of utilization by a large body of water and it then may prove necessary to effect bulk transfer of the natural gas by large tankers designed for such transport. Under these circumstances, economics dictate that the natural gas be liquefied so as to greatly reduce its volume and that it be transported at substantially atmospheric pressure. Under these conditions the LNG is at a temperature in the range of —258° F. This temperature represents the boiling point of methane at atmospheric pressure. It is to be noted, however, that the LNG often contains amounts of heavier hydrocarbons such as ethane, propane, butane and the like. These will vary the boiling range of the LNG so that it usually will fall somewhere between —240° F. and —258° F. However, nitrogen which is also typically present may cause the low end of the temperature range to get down as low as —270° F.

When the LNG arrives at the point of utilization, it is, of course, in liquefied form and, consequently, it becomes necessary to regasify it before it is used as a fuel. It is often highly desirable to utilize some of the higher molecular weight constituents as raw materials and as feedstocks for the production of various petrochemicals and for the manufacture of liquefied petroleum gas. In addition, it may prove necessary to adjust the heating value of the natural gas to conform with local requirements prior to its entrance into the actual fuel distribution system. This adjustment is conveniently achieved by the use of a reforming operation of the type to be more fully discussed hereinafter.

It will be appreciated that the reconversion of the LNG to a gaseous form requires the addition of a substantial amount of heat. When heating a cryogenic stream, such as LNG, many problems, both of an economic and technical nature, are often encountered. For example, when heating such streams, direct heat exchange is only feasible with heating streams which are dry since any

moisture present would freeze out and deposit and eventually block the heat exchangers employed. Coupling this with the fact that the least expensive heat sources are usually wet (e.g. cooling water, air and flue gas), it is not surprising that problems in this area are often encountered. In the past problems of this nature have been solved by using a separate intermediate heat exchange fluid contained in a closed cycle or the like. The function of this type of intermediate fluid system is to absorb heat from an available hot wet heat source and reject it to the cold LNG stream. However, there are numerous economic disadvantages which accompany such a system. For example, heat exchanger area requirements are, in effect, doubled since the number of needed exchangers is twice as high. Furthermore, separate facilities are required to store, handle and possibly even produce the separate intermediate exchange fluid.

In contrast, the teachings of the instant invention provide a method for heating cryogenic fluids such as LNG while avoiding the above-mentioned problem. Thus, a utilization of the method to be herein discussed results in a substantial reduction in heat-exchange area requirements and eliminates the need for separate handling facilities. Also, the need to make up losses in the amount of the intermediate heat exchange media is greatly reduced.

SUMMARY OF THE INVENTION

According to the instant invention the above highly desirable results may be achieved by using a recycled equilibrium process fluid in place of an intermediate heat exchange fluid. In a preferred embodiment of the invention, the LNG regasification is accomplished in combination with a reforming operation of the character to be hereinafter discussed. Thus, a cold liquid LNG stream is heated by direct contact with an equilibrium recycle stream which has, itself, been heated in an exchanger carrying the hot products of the reforming operation. According to applicants' process, as exemplified in this particular embodiment, the LNG feed is pressurized and partially heated and then flashed in a series of three flash drums. The cold liquid from the second of said drums is heated to a temperature in the range of approximately 25° F. to 80° F. by direct contact with a hot equilibrium recycle stream and the resulting mixture flows into the third drum. The equilibrium LNG recycle is obtained by drawing off a portion of the stream from the bottom of this third drum and heating it by use of one or more external process streams such as one or more of the hot streams available from the reforming operation. Some of the heat of the equilibrium recycle stream is then rejected to the incoming LNG feed in a series of exchangers and the remainder is rejected to the LNG entering the aforementioned third drum. By operating this third drum in the aforementioned temperature range and preferably about 30° F., freezing out is avoided in the exchange operation with the reformat streams. By direct injection of this recycle stream into the process stream entering the third drum, it is thus possible to effect a considerable amount of LNG heating without additional exchanger area.

Accordingly, an important object of this invention is to provide an efficient method for heating a cold fluid without the use of a separate intermediate heat exchange media.

Another important object of this invention is to facilitate the regasification of LNG so that it is in a suitable condition for delivery and use as a fuel.

Still another object is to provide a method in which LNG is heated by direct contact with a recycled equilibrium process fluid in place of separate intermediate heat exchange media.

Yet another object is to provide a system which requires less heat exchange area and no separate intermediate heat transfer fluid facilities thereby effecting substantial economies in equipment costs.

Other objects and a fuller understanding of the invention may be had by referring to the following description and claims taken in conjunction with the accompanying drawing.

In the figure a flow diagram illustrating a process according to the present invention is given.

Referring to the figure in detail, reference numeral 2 designates a stationary insulated storage tank which receives the LNG at atmospheric pressure from a tanker (not shown). The LNG in tank 2 will normally have a temperature of about -240° F. to -260° F. and may have, for example, the following composition range.

Table I

	Mole percent	
Methane	65-85	20
Ethane	7-17	
Propane	5-12	
Butanes and higher hydrocarbons	2-5	15
Nitrogen	0-2	
Others C ₅ +	0-1	25

The LNG from tank 2 is fed through the line 3 into pump 4 wherein its pressure is increased from about 15 p.s.i.a. to 1,100 p.s.i.a., preferably about 1,000 p.s.i.a. Pump 4 causes the pressurized LNG feed stream to flow through a series of heat exchangers, 8, 12 and 18, to be further discussed hereinafter. Upon exiting from exchanger 18 via the line 20 the LNG stream has been heated to a temperature in the range of -40° F. to 0° F. It is then fed into a first flashing drum 22. Drum 22 may be operated in the range of 1,000 to 1,100 p.s.i.a. with a preferable range of from 1,000 to 1,050 p.s.i.a. The flashed vapors from drum 22 will be mostly methane and will have a composition range such as shown in Table II, depending on the composition of the initial feedstock, and the exact operating temperatures and pressures of the drum.

Table II

	Mole percent or percent by volume	
Methane	80-90	45
Propane	1-5	
N ₂ +lighter	0-2	
Butane	0-2	50
Ethane	5-15	

From drum 22 these vapors are fed via conduit 24 to distribution pipeline 100. These vapors will represent about 40% to 80% of the original moles entering the LNG feed system. The liquid bottoms from drum 22 pass via line 26, valve 28 and line 30 into a second flashing drum 32. Drum 32 is operated in the pressure range of 200 to 500 p.s.i.a. with a preferable range of about 250 to 350 p.s.i.a. The liquid bottoms from drum 32 pass via the line 36 into a third flashing drum 42. This drum is operated in the pressure range of 200 to 350 p.s.i.a. with a preferable range of about 250 to 300 p.s.i.a. The equilibrium stream leaving the bottom of drum 42 is split into two fractions designated *a* and *b*, each having a temperature of about 25° F. to 80° F. Fraction *a* will normally be in the range of from 3 to 5 times as large as fraction *b*, and will vary somewhat depending upon the original composition of the entering LNG and the exact operating temperatures and pressures of drums 22, 32 and 42. However, since fraction *b* is held constant, the amount of fraction *a* is primarily dependent on the temperature of the heat source in exchanger 50. Upon its exit from drum 42 fraction *a*, which will have a temperature in the range of 25 to 80° F. and preferably about 30° F., is drawn into pump 46 and conducted via line 48 through the heat exchangers 50, 60 and 18. The temperature of fraction *a* as it leaves exchanger

18 will be in the range of 50° F. to 100° F. and preferably about 70° F. From exchanger 18 it is then injected into the line 36 at point X where it rejects its heat directly to the main LNG process stream so that the combined stream entering drum 42 will have a temperature in the range of about 25° F. to 80° F. By operating drum 42 in this temperature range and preferably in the range of 30° F. to 40° F., freezing out of moisture in the tubes of the reformate heat exchanger 50 is avoided. The upper operational temperature of drum 42 corresponds to the dew point of the fluid entering therein.

It will be understood that as long as the heat flowing into and out of fraction *a* recycle stream is in reasonable balance, no restrictions need be placed on the degree of vaporization which takes place in the recycle circuit. That is, when fraction *a* is injected into the cold LNG at point X, it can be either in the liquid, vapor or mixed phase. Here again, those skilled in the art will recognize a further improvement over conventional separate intermediate heat exchange fluid systems which require, in addition to good heat balances, that the intermediate fluid be only in the liquid phase at the accumulator drum. To insure this, the conventional systems must either use compression devices or vent the portion of the intermediate fluid that has vaporized and then supply additional liquid makeup to the heat exchange system. In either event the result would be a more complicated and more expensive system than is available using the teachings of the instant invention.

Under certain conditions, e.g. wide changes in feedstock composition, it is deemed advantageous to be able to bypass all or a portion of fraction *a* around point X. This may be accomplished by closing the valve 57 and opening the valve 59, which allows fraction *a* to enter the drum 47 through the line 53. By regulating the valve 49, in conjunction with valves 57 and 59, the change in the composition of fraction *a*, resulting from a change in the initial feedstock, may be made to take place over a longer period of time, thus giving plant operators more time to make adjustments. The recycled intermediate (i.e. fraction *a*) is eventually brought to equilibrium over this larger time period, at which point valve 59 is closed and the operation proceeds as originally discussed.

The vapors from drum 42 leave via line 40 and are then combined with fraction *b*. This combined stream, which represents approximately 10% to 30% of the original feed, enters a distillation column 56 via the line 58. The composition of the feed column 56 will range as indicated in Table III, again depending on the initial LNG feed composition and the various operating temperatures and pressures hereinbefore mentioned.

Table III

	Percent
Methane	20-25
Ethane	15-30
Butane	10-25
Propane	25-35
C ₆ +	0-3

60 Vapors (mostly C₁ and C₂) leave the top of column 56 via line 70 and pass through heat exchanger 12 where they serve to heat the main LNG feed stream from approximately -140° F. to about -90° F., and in so doing are partially condensed and collected in the separator drum 74. The liquid from drum 74 is refluxed via pump 78 back into the column 56. The vapors from drum 74 are combined with the overhead from drum 32 in the line 92. These vapors serve to add additional heat to the incoming LNG stream in heat exchangers 8 and 60. Upon their exit from the exchanger 8 as liquid, their pressure is increased to approximately 1,000 p.s.i.a. by pump 94. After leaving exchanger 60 as vapor, these vapors are passed to pipeline 100 and are ready for distribution.

65 The bottoms from column 56, pass through a reboiler 63 and will have the following composition range,

C ₂	0-30
C ₃	40-80
C ₄	20-60
C ₅₊	5-30

are split into three fractions. The first fraction is recycled

and operating in the aforesaid preferred temperature and pressure ranges, the following table indicates the approximate temperatures, pressures, and stream compositions present at various locations in the flow diagram. These locations are designated by referring to their assigned reference numerals appearing in the figure.

TABLE VI

Location	Tempera- ture (° F.)	Pressure (p.s.i.a.)	Typical stream composition (mole percent)								
			C ₁	C ₂	C ₃	C ₄	C ₅₊	CO ₂	N ₂	CO	H ₂
Line 3	-250	15	66.7	17.0	11.1	4.2	0.6	-----	0.4	-----	-----
Line 24	-15	1,000	84.0	10.7	3.7	0.8	0.1	-----	0.7	-----	-----
Line 30	-65	250	53.2	21.9	16.9	6.6	1.2	-----	0.2	-----	-----
Line 36 ¹	+30	250	21.3	32.0	31.6	12.7	2.4	-----	-----	-----	-----

											26.7
											9.6

¹ Before point "X".

back into the column via the line 64. This fraction represents about 50% to 70% and normally about 2/3 of the total bottoms product. The second fraction, representing from about 5% to 10% and normally about 1/20 of the total bottom product is fed to distribution pipeline 100 via the line 68. The third fraction, which represents from 25% to 35% of the bottoms product of column 56 and preferably about 1/10 of the number of original LNG feed moles, passes via the line 66 to a reforming complex represented by the box 80.

The composition of the material in the line 66 which comprise the heavy ends of the LNG feed will be in the following range:

Table IV

	Mole percent
C ₂	0-15
C ₃	45-65
C ₄	20-40
C ₅₊	0-5

In the reforming operation this composition is converted so that the reformate will have a composition as indicated in Table V.

Table V

	Mole percent
CO ₂	3-7
CO	1-2
H ₂	20-30
CH ₄	60-70

A great deal of H₂O comprising about 50% of the total molar flow will also be present. This water is removed after the reformate gas steam in line 82 is heat exchanged with the equilibrium recycle fraction *a* in exchanger 50 as hereinbefore discussed. After this heat exchange the reformate gas is ultimately fed via the line 86 to a compressor 88 where its pressure is raised to approximately 1,000 p.s.i.a and is then fed via line 90 into the distribution pipeline 100.

EXAMPLE

Starting with a typical LNG feedstock composed of:

	Mole percent
C ₁	66.7
C ₂	17.0
C ₃	11.1
C ₄	4.2
C ₅₊	0.6
N ₂ and other	0.4

It is to be understood that the foregoing arrangement can be modified in various details and need not necessarily be restricted to the processing of natural gas, per se. The flow diagram and description are given by way of example for the purposes of illustrating more clearly how the invention may be performed. Moreover, the operating percentages, temperatures and pressures specified hereinabove can be varied considerably for given mixtures. Accordingly, reference should be made to the following appended claims in determining the full scope of the invention.

What is claimed is:

1. A process for regassifying a feed of liquefied natural gas comprising in combination the steps of:

- pressuring and heating said liquefied natural gas feed;
- flashing said feed in a series of flashing drums;
- drawing of a portion of the stream from the bottom of the last drum in said series;
- heating said portion by use of an external process stream;
- using the heated portion resulting from step (d) in at least one heat exchanger to further heat the incoming natural gas feed; and then
- directly combining said portion with the material entering said last drum.

2. The process of claim 1 further characterized in that the heating of step (a) is partially accomplished by utilizing heat from the vapors leaving the top of the next to last drum in said series.

3. The process of claim 1 wherein the external process stream of step (d) is a hot reformate gas stream obtained by reforming the heavy ends of said natural gas feed.

4. In a process of the type wherein a liquefied natural gas feed is regassified, fractioned and subjected in part to a reforming operation, the improvement which comprises the following steps in combination:

- pressuring and heating said liquefied natural gas feed;
- flashing said pressurized and heated feed in a series of flashing drums;
- drawing of a portion of the stream from the bottom of the last drum in said series, said portion being in equilibrium with the liquid in said last drum;
- heating said portion by passing it in indirect heat exchange with a hot process stream from said reforming operation;
- passing the heated portion resulting from step (d) through at least one heat exchanger to further warm the incoming natural gas feed; and
- directly combining said portion with the material stream entering said last drum whereby said last mentioned stream is further heated.

5. The process of claim 4 further characterized in that the heating in step (a) is accomplished by indirect heat

3,446,029

7

exchange with process streams resulting from the fractionation of said liquefied natural gas feed.
